ALBERT J. ROSENTERETER, OF BOONTON, NEW JERSEY, ASSIGNOR TO EDGAR ZABRISKIE, OF MAPLEWOOD, NEW JERSEY, AND FRANK E. HUTCHINS, OF NEW YORK, N. Y.

SAFETY MECHANISM FOR ELEVATOR-SHAFT DOORS.

1,353,852.

Specification of Letters Patent. Patented Sept. 28, 1920.

Application filed December 17, 1919. Serial No. 345,556.

To all whom it may concern:

Be it known that I, ALBERT J. ROSENTERETER, a citizen of the United States, and a resident of Boonton, in the county of Morris and State of New Jersey, have invented certain new and useful Improvements in Safety Mechanisms for Elevator-Shaft Doors, of which the following is a specification.

The invention pertains more especially to mechanism in or connected with an elevator shaft for controlling the motive power and operable on the opening of any sliding door at the several floors of the building, when the car comes to rest thereat, to cut off the power from the car, the power being automatically restored when the sliding door is closed or has nearly reached its closed position.

The object of the invention is to prevent the accidents which arise from elevator cars being started in motion from a floor of a building before the door at such floor has been wholly or substantially closed.

Many accidents have occurred by persons hurrying or attempting to hurry through a partly closed doorway of an elevator shaft to enter a car after the car has started or is about to start in movement, and such accidents are obviated by my invention which prevents the car from moving until the door has been wholly or substantially closed.

In carrying out my invention I extend a vertical connection, as a single cable or wire rod, the length or height of the elevator shaft in a straight line, the connection preferably being provided at both ends with weights or other tensioning means. This connection, cable or rod extends through pivoted lever arms secured to the frame of the several doors, and above said levers said connection has buttons or shoulders or the like thereon to be respectively engaged by any lever arm that may be moved upwardly. The lever arms referred to have a member which extends into the elevator shaft and through the end of this member the vertical connection or cable passes, and said lever arms are adapted to be actuated, during the opening movement of the door, by latch mechanism mounted on the door to be manually operated by the attendant on the car when the car comes to a stop at a floor of the building, and when the door is opened

said mechanism, acting on one end of said lever arm, moves the other end or member of said arm against a button on the vertical connection and causes said connection or cable to move a part connected with a cut-out or switch-box in the basement or at the foot of the elevator shaft or any other convenient location, and thereby effect the cutting off of the power from the car, the power remaining cut off from the car during all of the period that the door is open. The power is automatically restored to the car when the door is moved to its closed position, the door latch mechanism, or that part thereof carried by the door, then permitting the movement of the aforesaid lever arm and said cable or connection in a downwardly direction.

The mechanism of my invention comprises the aforesaid vertical connection or cable having the buttons or shoulders thereon, the pivoted lever arm secured to the door frame at each floor of the building, a locking dog also secured to the door framing at each floor of the building and adapted, when the door is opened, to lock the lever arm in position to maintain the power cut off from the car or hoist, and a suitable mechanism secured on the door embracing a latch for locking the door in closed position and which latch embodies means for displacing the aforesaid dog when the door is closed, thereby releasing the lever arm to be tilted downwardly at its outer end by said connection or cable for automatically restoring motive power to the car, and which means on the opening of the door acts on said lever arm to set the same for automatic engagement by said dog, whereby to maintain the power cut off from the car while the door is open.

The invention will be fully understood from the detailed description hereinafter presented, reference being had to the accompanying drawings, in which:

Figure 1 is a vertical section, partly broken away, through an elevator shaft and showing the shaft-side of the several doors at the floors of the building;

Fig. 2 is a vertical section, partly broken away, through one of the shaft doors and adjacent parts and illustrating more particularly the features embraced in my invention.

tion, the section being on the dotted line 2-2 of Fig. 5;

Fig. 3 illustrates the cut-out or switch box located at the foot of the elevator shaft to be operated from the vertical connection or cable extending through the shaft;

Fig. 4 is a corresponding view of a cut-out or switch-box which, when so desired, may be located at the top of the elevator shaft as a substitute for the cut-out or switch-box shown in Fig. 3;

Fig. 5 is an elevation, on a larger scale, showing one of the sliding doors with the mechanism thereon and the mechanism operable therefrom;

Fig. 6 is an elevation, partly broken away, on a larger scale, of a sliding door, sliding door frame and elevator shaft equipped with the mechanism embodying my invention, the door being shown in closed position, and

Fig. 7 is a corresponding view of the same illustrating the relation of the parts when the door has been moved toward its open position and the power has been cut off from the car.

In the drawings, 10 designates the customary sliding doors for an elevator shaft, 11 stationary or panel doors of usual character, 12 the framing about the doors, and 13 the several floors of the building.

Each door 10 is equipped with door latching and opening mechanism, shown in the present instance as comprising a vertical rod 14 having an upper end latching portion 15 which is polygonal in cross-section and a lower tubular or handle portion 16 adapted to telescope on a pin 17 which is secured to a bracket 18 fastened against the door.

Within the tubular handle portion 16 of the rod 14 is confined a coiled spring 19 whose lower end has a bearing on the upper end of the pin 17 and whose upper end bears against the inner top surface of the said handle portion 16, and the tension of said spring 19 is to move the rod 14 and parts connected therewith in an upwardly direction, causing the upper end 15 of the rod 14 to act in the nature of a spring latch.

The pin 17 serves to retain the lower tubular end of the rod 14 in correct relation to the door 10, and the upper portion 15 of said rod is adapted to guide within a bracket 20 fastened to the door 10 adjacent to the upper edge thereof. The upper end of the latch portion 15 of the rod 14 is inclined or curved outwardly and downwardly, as at 21, and said portion 15 is equipped with a transverse pin 22, whose purpose will be herein-after described.

In respect to the mechanism embraced within the present invention, the only portion thereof carried by the door 10 consists of the rod 14 and parts hereinbefore enumerated connected therewith. The door 10 is

suitably suspended by hangers of known type and requiring no specific mention herein, and the door itself, together with the panel door 11, may be of any usual or suitable construction and mounting.

70

Upon the door framing adjacent to the upper left hand corner of the door, viewed from the shaft-side of the door, is secured a cast bracket 23 having a vertical member 24 engaging and secured to the jamb of the door, a horizontal inwardly extending elongated member 25, and a lower vertical recess 26 adjacent to the member 24, and at its inner vertical edge affording a shoulder 27 to be engaged by the upper end of the latch-portion 15 of the rod 14, as shown in Fig. 6. The member 25 of the casting 23 is formed with a web portion 28 and along the edges thereof with an unbroken transverse flange 29, said flange being inclined downwardly 85 and outwardly at its inner end portion, as at 30, and then extending outwardly on horizontal lines, as at 31, and finally extending along the edges of the opening 26, as shown in Fig. 7. The casting 23 is in one integral 90 piece, and hence is of simple and durable construction and may be readily applied to position.

At its lower outer corner the casting 23 has pivotally mounted thereon, by means of a pin 32, a two-armed lever in one integral casting, the inner arm of said lever being numbered 33 and the outer arm of said lever being designated by the numeral 34. I number the two-armed lever as a whole 35. 100 The member 33 of the lever 35 is formed with a web portion 36 and an upper transverse flange 37, and the member 34 of said lever is formed with a web portion 38, an upper transverse flange 39 and a bifurcated 105 outer end portion or auxiliary arm 40, which receives within its slot the vertical connection, cable or wire rod 41, on which is adjustably secured buttons or shoulders 42, the button or shoulder 42 at each floor 110 of the building being directly over and engaging the upper surface of the auxiliary arm 40. The buttons 42 may be of any suitable type and constitute shoulders against which the respective arms 40 may act to 115 move the vertical connection 41 upwardly and which may act against said arms 40 during the downward movement of the connection so as to tilt the two-armed lever 35 from the position shown in Fig. 7 to that 120 illustrated in Fig. 6. The two-armed levers 35 are carried by and supported from the castings 23 and offset from the vertical plane of the sides of said castings as indicated in Fig. 2.

The castings 23 are each formed with a lug 43 upon which is pivotally mounted the upper end of a weighted arm or gravity dog 44 which preferably has downwardly diverging side edges and a curved lower end, 130

125

as clearly represented in Fig. 7. The dog is on the same vertical plane with the arm 33 of the lever 35, as shown in Fig. 2. When the door 10 is in closed position it is, as 5 hereinbefore mentioned, latched by the engagement of the portion 15 of the rod 14 with the shoulder formed by the flange 27 at the inner vertical edge of the recess 26 in the casting 23, as shown in Fig. 6, and at 10 this time the dog 44 has been tilted to one side by and rests upon the transverse pin 22 of the latch member 15, as shown in Fig. 6.

When the rod 14 is pulled downwardly in 15 opposition to the force of the spring 19, and the door 10 is then moved to open by lateral pressure applied against the handle portion 16 of said rod, the latch member becomes lowered from the recess 26 of the casting 23 20 and travels with the door 10 during the opening movement of the same, the pin 22 on said latch member 15 then riding against the upper flange 37 on the arm 33 of the lever 35 and causing said arm 33 to turn 25 downwardly to a horizontal position and the arm 34 of said lever to turn upwardly to a horizontal position or to the position in which it is shown in Fig. 7, and the dog 44 automatically at this time swinging to a 30 vertical position, following the pin 22, and becoming arrested directly above the lever-arm 33, as shown in Fig. 7, in which position said dog serves to lock the lever 35 stationary. I provide the dog 44 with a stop 45, 35 which, by engaging a part of the casting 23, serves to arrest said dog when the same attains the vertical position shown in Fig. 7. When the door is in closed position the latch member 15 and dog 44 will be in the 40 respective positions in which they are shown in Fig. 6, the door then being closed and latched, and when the door is to be opened the rod 14 is drawn downwardly and the handle 16 is used for sliding the door toward 45 its open position, and at this time the pin 22 of the latch member 15 rides against and along and acts to turn the inner end or arm 33 of the lever 35 downwardly and the dog 44 automatically turns to position for 50 locking said arm 33 in the position given to it by the pin 22, so that after the pin 22 leaves the arm 33, due to the continued opening movement of the door 10, said dog may maintain the lever 35 in the position 55 imparted to it by the pin 22 during the first portion of the opening movement of the door 10. The mechanism connected with the door framing thus consists simply of the casting 23, lever 35 and dog 44, and these 60 parts may all be assembled and secured to the door framing by means of screws 46 (Fig. 2) or in any other convenient way.

One purpose of my invention is, particularly, to provide means operable on the 65 opening of a door 10 for automatically cut-

ting off motive power from a car whose attendant opens the door after bringing his car to rest thereat, and for restoring power to the car on the closing of the door, and these means reside more particularly in the 70 vertical connection 41 having thereon shoulders or buttons 42 and the levers 35 whose arms 34, by means of the extensions 40, extend below and coöperate with the said shoulders or buttons 42.

The vertical connection 41 extends substantially the full height of the elevator shaft and is preferably a single cable, wire rod or the like, whose upper end extends over a pulley 96 at the top of the elevator 80 shaft and has a tensioning weight 47 connected therewith, as shown in Fig. 1. The lower end of the connection 41 has secured to it a tensioning weight 48, and above said weight said connection 41 is equipped with 85 two shoulders or buttons 49, 50 which are reasonably close together and receive between them the bifurcated end of a lever arm 51 which is pivotally secured at 52 and has a bell-crank lever 53 connected with it, 90 said lever 53 being mounted in a cut-out or switch box 54 and carrying at its lower end a conducting strip 55 adapted to extend across and connect two terminal plates 56 which are edge to edge and one of which has 95 one circuit wire 57 connected with it and the other of which has another circuit wire 58 in electrical connection therewith (Fig. 3). The cut-out or switch box 54 is an ordinary type of cut-out or switch box, and I do not 100 make any specific claim to the features thereof. When the parts are in the position shown in Fig. 3, the conducting strip 55 by connecting the two edge to edge plates 56 establish the circuit for moving the car, 105 not shown, and at this time all of the doors 10 in the elevator shaft are in closed position and in such position secured by the latch members 15 at the respective floors.

When the car is arrested at any floor of 110 the building and the attendant on the car starts to open the door 10 thereat, he will pull the rod 14 downwardly to free the latch member 15 from the shoulder formed by the inner edge of the recess or keeper 115 26 and then slide the door to its open position. The movement of the door toward its open position will result in the door carrying the pin 22 against the arm 33 of the lever 35 and turning said arm downwardly 120 and the arm 34 of said lever upwardly, and this operation results in said arm 34, by engaging the button or shoulder 42, moving the vertical connection 41 upwardly, the slack being taken up by the weight 47, and the upward movement of the connection 41 results in the free end of the lever arm 51 being elevated and effecting the elevation 125 of the conductor 55 from the switch arms 56, thereby breaking the circuit and cutting 130

off the motive power from the car. The connection 41 will remain in position cutting off the motive power from the car so long as the arm 34 of the lever 35 maintains its pressure against the shoulder or button 42 on said connection, and in order that the motive power shall be cut off from the car during all of the time that the door 10 is in its open position, I provide the dog 44 which will lock the lever 35 in the position in which it is shown in Fig. 7, during all of the period that the door 10 is in an open position. When the door 10 is closed it is desirable that the motive power be restored to the car, and on the closing of the door 10 the pin 22 will first swing the dog 44 from the lever arm 33, allowing the lever 35 to tilt from the position in which it is shown in Fig. 7 to that illustrated in Fig. 6, and the upper end of the latch member 15 will enter the recess 26 of the casting 23 and latch the door 10 in closed position. When the dog 44 is swung from engagement with the arm 33 of the lever 35, the weight 48 at the lower end of the connection 41 will overbalance the weight 47 at the upper end of said connection and pull the connection downwardly so that the shoulders or buttons thereon will maintain their engagement with the outer end portions of the arms 34 of the levers 35 and at the same time restore the conducting strip 55 to its operative position, completing the circuit for the motive power for the car. As a substitute for the mechanism shown in Fig. 3 at the lower end of the elevator shaft, for cutting off and restoring the motive power employed to operate the car, I can make use of equivalent mechanism applied at the upper end of the elevator shaft, and this mechanism I illustrate in Fig. 4, in which 41 denotes the vertical connection, 59 a weight thereon at the lower end of the elevator shaft, 60 a pivoted lever having one end engaged by said connection 41 and provided at its other end with a weight 62, 63 a switch or cut-out box, 64 a bell crank lever mounted therein having one arm in engagement with the lever 60 and carrying a conducting strip 65 at its other end, 66 a pair of switch arms to be connected by the conductor 65, 67 one of the circuit wires connected to one of the members 66, and 68 the other circuit wire connected to the other of said members 66. When the parts are in the relative relation shown in Fig. 4, the motive power will be on the car, and the car may be set in motion, as usual. When a door at any floor of the building is opened and the lever 35 at such floor is tilted upwardly, by the opening of the door, to engage a button or shoulder 42 on the connection 41 and lift said connection upwardly, in opposition to the weight 59, the weight 62 will descend and turn the longer

arm of the lever 60 downwardly so as to release the bell crank lever 64 and effect the movement of the conductor 65 from the switch members 66, thereby breaking the circuit. When the door 10 is closed the weight 59 will restore the lever 35 which had been operated, to its normal position, shown in Fig. 6, and cause the lever 60 to turn upwardly at its longer arm, lifting the weight 62 and restoring the conductor 65 against the switch members 66, thereby completing the circuit. The details of the mechanisms shown in Figs. 3 and 4 are not novel nor do they specifically form any part of my invention. Other forms of switch or cut-out mechanism may be employed in connection with the vertical connection 41 in carrying out the purpose of my invention, and my invention, therefore, resides more particularly in said connection 41 and the means connected with the door and door framing for assuring the proper operation of the same for cutting off the motive power from the car when the shaft-door is opened and restoring said power to the car when the shaft door is closed.

My invention has been so fully described hereinbefore that it is believed that the construction and operation of the same will be fully understood without extended additional explanation. I may add that when the door 10 is moved to closed position, the upper end of the latch-member 15 will ride against the downwardly and outwardly inclined flange 30 of the casting 23 and then pass along below and against the flange 31 of said casting, compressing the spring 19, and, finally, when the pin 22 moves the locking dog 44 to releasing position and the upper end of the latch-member 15 has reached the recess 26 of said casting 23, the spring 19 will, by its expansion, move the upper end of said latch-member upwardly into said recess, where the same will be confined by the shoulder 27. The features constituting my invention are of very durable and simple character, easy to manufacture and convenient to install. My invention provides very satisfactory means for application to elevator-shafts and doors and the same may be installed at comparatively small expense.

What I claim as my invention and desire to secure by Letters-Patent, is—

1. In elevator-shaft and elevator-shaft door mechanisms, in combination, a vertical connection extending the height of the shaft and adapted to have limited vertical movement, a cut out switch for cutting off the car motive power operable from said connection, shoulders on said connection at the several floors of the building, levers on the door framing at said floors having one arm disposed to engage the respective shoulders on and move said connection, a manually

operative door-latch on each door, shoulders on the door framing to engage the latches when the doors are closed, and means carried by the latches for engaging said levers respectively on the opening of a door to actuate the same against said shoulders on said connection respectively for moving said connection lengthwise to break the circuit at said switch.

2. In elevator-shaft and elevator-shaft door mechanisms, in combination, a vertical connection extending the height of the shaft and adapted to have limited vertical movement, a cut out switch for cutting off the car motive power operable from said connection, shoulders on said connection at the several floors of the building, levers on the door framing at said floors having one arm disposed to engage the respective shoulders on and move said connection, a manually operative door-latch on each door, shoulders on the door framing to engage the latches when the doors are closed, means carried by the latches for engaging said levers respectively on the opening of a door to actuate the same against said shoulders on said connection respectively for moving said connection lengthwise to break the circuit at said switch, and means for automatically engaging said levers on the opening of the respective doors and maintaining them in circuit breaking position while the door is open.

3. In elevator-shaft and elevator-shaft door mechanisms, in combination, a vertical connection extending the height of the shaft and adapted to have limited vertical movement, a cut out switch for cutting off the car motive power operable from said connection, shoulders on said connection at the several floors of the building, levers on the door framing at said floors having one arm disposed to engage the respective shoulders on and move said connection, a manually operative door-latch on each door, shoulders on the door framing to engage the latches when the doors are closed, means carried by the latches for engaging said levers respectively on the opening of a door to actuate the same against said shoulders on said connection respectively for moving said connection lengthwise to break the circuit at said switch, means for automatically engaging said levers on the opening of the respective doors and locking them in circuit breaking position while the door is open, and means for retiring said locking means from said levers on the closing of the door to permit said connection to move said levers to initial position and re-make the circuit at said switch.

4. In elevator-shaft and elevator-shaft door mechanisms, in combination, a vertical connection extending the height of the shaft and adapted to have limited vertical

movement, a cut out switch for cutting off the car motive power operable from said connection, shoulders on said connection at the several floors of the building, pivoted levers on the door framing at said floors having one arm disposed to engage the respective shoulders on and move said connection, vertically movable latch rods on the doors having latch members at their upper ends, shoulders on the door framing to engage the latches when the doors are closed, and pins carried by said latches for respectively engaging the other arms of said levers on the opening of the respective doors for tilting said levers against said shoulders on said connection respectively for moving said connection lengthwise to break the circuit at said switch.

5. In elevator - shaft and elevator - shaft door mechanisms, in combination, a vertical connection extending the height of the shaft and adapted to have limited vertical movement, a cut out switch for cutting off the car motive power operable from said connection, shoulders on said connection at the several floors of the building, pivoted levers on the door framing at said floors having one arm disposed to engage the respective shoulders on and move said connection, vertically movable latch rods on the doors having latch members at their upper ends, shoulders on the door framing to engage the latches when the doors are closed, pins carried by said latches for respectively engaging the other arms of said levers on the opening of the respective doors for tilting said levers against said shoulders on said connection respectively for moving said connection lengthwise to break the circuit at said switch, and means for automatically engaging said levers on the opening of the respective doors and locking them in circuit breaking position while the door is open.

6. In elevator - shaft and elevator - shaft door mechanisms, in combination, a vertical connection extending the height of the shaft and adapted to have limited vertical movement, a cut out switch for cutting off the car motive power operable from said connection, shoulders on said connection at the several floors of the building, pivoted levers on the door framing at said floors having one arm disposed to engage the respective shoulders on and move said connection, vertically movable latch rods on the doors having latch members at their upper ends, shoulders on the door framing to engage the latches when the doors are closed, pins carried by said latches for respectively engaging the other arms of said levers on the opening of the respective doors for tilting said levers against said shoulders on said connection respectively for moving said connection lengthwise to break the circuit at said switch, and means for automatically

- engaging said levers on the opening of the respective doors and locking them in circuit breaking position while the door is open, said locking means when in operative position being in the path of said pins, and said pins on the closing movement of the doors being adapted to retire said locking means from said levers to permit said connection to tilt said levers to their initial position.
7. In elevator-shaft and elevator-shaft door mechanisms, in combination, a vertical connection extending the height of the shaft and adapted to have limited vertical movement, a cut out switch for cutting off the car motive power operable from said connection, shoulders on said connection at the several floors of the building, spring-pressed latch rods on the doors having latch members at their upper ends, metal frames secured to the door framing at the several floors having recesses to receive and afford engaging shoulders for the said respective latches carried by the doors, levers pivotally mounted on said metal frames having one arm disposed outwardly to engage a shoulder on and move said connection and another arm extended inwardly along the lower portion of said metal frame, pins carried by said latches for respectively riding against the inwardly extending arms of said levers on the opening of the respective doors for tilting said levers against said shoulders on said connection respectively for moving said connection lengthwise to break the circuit at said switch, and pivoted gravity dogs pivotally mounted on said metal frame for automatically engaging said levers on the opening of the respective doors and locking them in circuit breaking position while the door is open, said dogs when in operative position being in the path of said pins, and said pins on the closing movement of the doors being adapted to engage and turn said dogs from engagement with said levers to permit said connection to tilt said levers to their initial position.
8. In elevator-shaft and elevator-shaft door mechanisms, in combination, a vertical connection extending the height of the shaft and adapted to have limited vertical movement, a cut out switch for cutting off the car motive power operable from said connection, shoulders on said connection at the several floors of the building, spring-pressed latch rods on the doors having latch members at their upper ends, metal frames secured to the door framing at the several floors having recesses to receive and afford engaging shoulders for the said respective latches carried by the doors, levers pivotally mounted on said metal frames having one arm disposed outwardly to engage a shoulder on and move said connection and another arm extended inwardly along the lower portion of said metal frame, pins carried by said latches for respectively riding against the inwardly extending arms of said levers on the opening of the respective doors for tilting said levers against said shoulders on said connection respectively for moving said connection lengthwise to break the circuit at said switch, and gravity dogs pivotally mounted on said metal frame for automatically engaging said levers on the opening of the respective doors and locking them in circuit breaking position while the door is open, said dogs when in operative position being in the path of said pins, and said pins on the closing movement of the doors being adapted to engage and turn said dogs from engagement with said levers to permit said connection to tilt said levers to their initial position.

Signed at New York city, in the county of New York and State of New York, this 15th day of December, A. D. 1919.

ALBERT J. ROSENTRETER.
